UNITED STATES PATENT OFFICE.

JOHN K. ROBINSON, OF CHICAGO, ILLINOIS, ASSIGNOR TO THE PALMETTO FIBRE COMPANY, OF ILLINOIS.

DESIGN FOR A BRUSH.

SPECIFICATION forming part of Design No. 25,894, dated August 4, 1896.

Application filed June 15, 1896. Serial No. 595,688. Term of patent 14 years.

To all whom it may concern:

Be it known that I, JOHN K. ROBINSON, a citizen of the United States, residing at Chicago, in the county of Cook and State of Illinois, have invented and produced a new and original Design for Brushes, of which the following is a specification, reference being had to the accompanying drawings, in which—

Figure 1 is a side elevation of a brush embodying my improved design. Fig. 2 is a top plan view of the same. Fig. 3 is a bottom plan view of the same. Fig. 4 is an end elevation of the same.

The leading features of my design consist of the brush-block, presenting in outline a rear flat face and a front flat face joined at their ends by outward curves, bristles radiating from the front face of the block and its curved ends and terminating at their ends in a line parallel with the curved ends of the block and its front flat face, and a handle rising from the opposite sides of the brush-block and extending transversely in a substantially semicircular path beyond the rear face of the block.

A represents the brush block or body, presenting in outline, as viewed from the side, as in Fig. 1, a front flat face *a* and a rear flat face *a'*, which are joined at their ends by outward curves *a²*, forming a continuation of the front face. Bristles *B* radiate from the front face of the block and its curved ends and terminate at their active ends in a line *b*, extending parallel to the front face and the curved ends *a²*. A handle *C* extends from the opposite sides of the block and presents an outline, as viewed from the side, as in Fig. 1, of rectangular form, consisting of the two parallel sides *c*, connected at their ends by

lines *c'* and *c²*, extending longitudinally of the brush-block.

As viewed from the rear, as in Fig. 2, the brush-block presents an outline of rectangular form, the bristles *B* extending beyond the ends of the block and terminating in lines *b'*, parallel to the ends of the block. The handle *C* presents an outline consisting of the transverse lines *c²*, parallel to each other and connected at their ends by lines *c'*, extending longitudinally of the block,

As viewed from the front, the block presents in outline two parallel sides *a*, the body of bristles *B* terminating in lines extending inward of the sides of the block and beyond the ends of the same and parallel therewith. The handle *C* at the sides of the block presents in outline lines *c'*, extending parallel to and a slight distance from the same.

As viewed from the end, as in Fig. 4, the block presents a rear flat face *a'*, bristles extending from the front face of the block and terminating in a line parallel therewith, as *b*, and the handle *C*, rising from the sides of the block and describing substantially a semicircular curve *c'* beyond the rear face of the block.

Having thus described my invention, what I claim is—

The design for a brush substantially as herein shown and described.

In testimony whereof I have hereunto set my hand this 4th day of June, 1896, at Chicago, Illinois, in the presence of two attesting witnesses.

JOHN K. ROBINSON.
